CLAIM

The ornamental design for modular computer workstation as shown and described.

DESCRIPTION

1. Modular computer workstation

1.1 : Perspective view in interconnected state

1.2 : Perspective view in interconnected state

1.3 : Perspective view in interconnected state

1.4 : Perspective view in disconnected state

1.5 : Perspective view in disconnected state

1.6 : Left view in interconnected state

The modular workstation has two interconnectable units, i.e., an adjustable chair and an adjustable table, shown in different views with different adjusted positions; broken lines are for illustrative purposes only and form no part of the claimed design.
